CHUCK SHIFTING MECHANISM AND SLAT FEEDING MECHANISM FOR LIDDING MACHINES

Hale Paxton, Redlands, Calif., assignor to Paxton Credit Corporation, Sanger, Calif., a corporation of California

Application December 20, 1932, Serial No. 648,081

14 Claims. (Cl. 1—10)

My invention relates to nailning machines and is particularly useful in applying lids to crates or boxes of different widths.

In the packing of certain agricultural products for shipment different sized crates or boxes are used for the different varieties of fruits and vegetables, these crates usually being approximately equal in length and different in height and width. When certain fruits and vegetables are in season at the same time it is often necessary for one packing house to pack several varieties of produce simultaneously, and the different sized crates must be segregated for the lidding operation as the lidding machines are usually adjusted to receive a crate of a certain width and the machines must be readjusted for crates of different sizes.

An object of my invention is to provide a lidding machine in which the lid nail chucks are automatically shiftable to proper alignment with crates or boxes of various widths.

Another object of my invention is the provision of a lidding machine in which separate lid slats are automatically fed to position below the nail chucks.

A further object of my invention is to provide a crate or box lidding machine in which the lid slats are automatically spaced to fit crates or boxes of various widths.

Further objects and advantages will become apparent in the following description taken in connection with the accompanying drawings, in which:

Fig. 1 is a front elevational view of a preferred form of lidding machine of my invention.

Fig. 2 is a vertical sectional view taken on the line 2—2 of Fig. 1.

Fig. 3 is an enlarged sectional view of a portion of the machine shown in Fig. 2.

Fig. 4 is a view similar to Fig. 2 showing a stage of operation of the preferred machine of my invention.

Fig. 5 is an enlarged, fragmentary, vertical sectional view taken on the line 5—5 of Fig. 4.

Fig. 6 is an enlarged fragmentary perspective view of a portion of the machine shown in Figs. 4 and 5.

Fig. 7 is a fragmentary vertical sectional view taken on the line 7—7 of Fig. 6.

Fig. 8 is a view similar to Figs. 2 and 4 showing a stage of operation subsequent to that shown in Fig. 4.

Fig. 9 is an enlarged, fragmentary, horizontal sectional view taken on the line 9—9 of Fig. 8.

Fig. 10 is a fragmentary sectional view taken on the line 10—10 of Fig. 9.

Fig. 11 is a view similar to Figs. 2, 4 and 8 showing a stage of operation subsequent to the stage shown in Fig. 8.

Figs. 12 to 15 inclusive are fragmentary, semi-diagrammatic views illustrating the operation of a portion of the preferred machine of my invention.

Fig. 16 is a fragmentary elevational view taken on the line 16—16 of Fig. 12.

Fig. 17 is a detail perspective view of one of the elements shown in Figs. 12 to 16 inclusive.

Fig. 18 is a horizontal sectional view taken on the line 18—18 of Fig. 1.

Fig. 19 is an enlarged fragmentary view of a portion of the machine as shown in Fig. 18. 15

Fig. 20 is a fragmentary view showing the operation of the parts shown in Fig. 19.

Fig. 21 is a fragmentary, vertical sectional view taken on the line 21—21 of Fig. 1.

Fig. 22 is a fragmentary, vertical sectional view 20 showing a portion of a modified form of lidding machine of my invention.

Fig. 23 is a view similar to Fig. 22 showing the mode of operation of the parts disclosed therein.

Fig. 24 is a fragmentary elevational view taken 25 in the direction of the arrow 24 of Fig. 22.

Fig. 25 is a fragmentary, vertical sectional view taken on the line 25—25 of Fig. 24, and

Fig. 26 is a fragmentary, horizontal sectional view taken on the line 26—26 of Fig. 22. 30

Referring specifically to the drawings, a lidding machine 10 comprising a preferred embodiment of my invention is shown in Figs. 1 to 21 inclusive, this machine including a frame 11, an elevator 12, a work centering mechanism 13, a nailng mechanism 14, a chuck shifting mechanism 15, a slat supporting mechanism 16, and a slat feeding mechanism 17.

The frame 11

The frame 11 includes a suitable base 20, the latter supporting a pair of vertical side standards 21. Fixed to the standards 21, as shown in Figs. 1 and 2, are front and rear horizontal angle iron bars 22 and 23 respectively. Welded or otherwise secured to the upper ends of the standards 21, as shown in Fig. 2, are forwardly extending brackets 24 which support opposite ends of front and rear horizontal bars 25 and 26.

Mounted on opposite ends of each of the bars 25 and 26 are front and rear brackets 27 and 28 respectively, to the upper ends of which pairs of bars 29 are fixed as shown in Figs. 1 and 2. Mounted on the lower ends of the brackets 27 and 28 are bars 30, these being parallel with the 55

bars 29, it being noted in Fig. 2 that the bars 30 extend rearward beyond the side standards 21 and are braced at their rear extremities by a tie rod 31.

5 *The elevator 12*

The elevator 12 includes a hydraulic cylinder 33 and a box supporting platform 34, as shown in Fig. 1. The cylinder 33 has a piston (not shown) from which a piston rod 35 extends vertically. The platform 34 includes a frame 36 which is secured to the upper end of the piston rod 35, the frame 36 having grooved rollers 39 mounted on opposite ends thereof, it being noted in Fig. 1 that the rollers 39 are positioned to embrace the inner edges of the side standards 21 so as to guide the platform 34 in its vertical movement relative to the standards 21. Rotatably mounted on the frame 36 of the platform 34 are box rollers 37. Suitably mounted at opposite ends of the platform frame 36 are box or crate stops 38 which are adapted to automatically position a box at a predetermined location on the platform 34 relative to the longitudinal axis of the box. A complete disclosure of the structure and operation of the stops 38 can be found in my copending application for U. S. Letters Patent, Serial No. 468,680, filed July 17, 1930, for Automatic box stop for lidding machine.

Fixed to the rear edge of the frame 36 of the platform 34 are vertical plates 40. Each of the plates 40 is positioned adjacent opposite ends of the frame 36 and is formed to provide an apertured ear 41 and a rearwardly extending projection 42, as shown in Fig. 2.

35 Rotatably mounted on the front edge of each of the plates 40 is a pair of grooved rollers 43, as shown in Figs. 2 and 18. Carried by the rollers 43 on the plates 40 is a crate ejector 44 which includes a horizontal bar 45, as shown in Figs. 2 and 18, this bar having a plate 46 fixed thereto upon which a box engaging finger 47 is pivotally mounted, as shown in Fig. 19. The finger 47 includes a bar 48 which is normally urged against a stop pin 49 by a torsion spring 50, as clearly shown in Fig. 19. Pivoted on the free end of the bar 48 is an extension 52 which is urged against a stop pin 53 by a torsion spring 54. The bar 44 is adapted to be reciprocated horizontally in response to vertical movement of the platform 34 by a diagonal bar 56 clearly shown in Figs. 1 and 18. The bar 56 includes a tubular portion 57 which is pivotally mounted at its lower end on the horizontal bar 22 of the frame 11 at a point indicated at 55 in Fig. 1. Slidably received in the upper end of the tube 57 is a rod 58, the free end of which is pivotally mounted on the bar 44. Mounted on the rod 58 is a compression spring 59, opposite ends of which are fixed to the tube 57 and the rod 58 as shown in Fig. 1.

60 Hung below opposite ends of the platform 35 in transverse relation thereto are parallel bars 62 as shown in Figs. 1 and 2.

65 *The box centering mechanism 13*

The box centering mechanism 13 includes a pair of units 63 and 64 mounted on opposite ends of the platform frame 36, as shown in Fig. 1. As the units 63 and 64 are identical, a detailed description of but one of the units will be set forth, and like reference numerals will denote like parts in each of these units.

As shown in Fig. 2, the unit 64 of the centering mechanism 13 includes a pair of lever arms 70 and 71, these being pivotally mounted on one of the

bars 62, the arm 70 having a downward extension 72, on the lower end of which a bored block 73 is pivotally mounted. Secured to the upper ends of the arms 70 and 71 of each of the units 63 and 64 are front and rear guide rails 75 and 76 respectively, these being curved at their ends as shown in Fig. 18. Fixed to the rear guide rail 76, as shown in Figs. 2 and 18, is a pair of apertured ears 77, the purpose of which will become apparent hereinafter in connection with the chuck shifting mechanism 15. The arms 70 and 71 of the unit 64 are connected by a diagonal link 80, as shown in Fig. 2, so that they swing inwardly and outwardly in unison. Pivoted on the bar 62 is a depending arm 81 having an ear 82 and an outwardly extending pin 83 provided on the lower end thereof. Pivoted on the ear 82 of the arm 81 is a rod 84, the opposite end of which is slidably received by the aforementioned block 73 on the extension 72 of the arm 70.

Fixed on the rod 84 at opposite sides of the block 73 is a pair of collars 85 and 86, the collar 85 being normally held in contact with the block 73 by a compression spring 87, the latter being mounted on the rod 84 between the block 73 and the collar 86, as shown. The arms 70 and 71 are normally urged to the position shown in Fig. 2 by a contractile spring 98 which is suspended from the extension 72 of the arm 70 to the pivot point of the depending arm 81, as shown in Fig. 2.

Fixed to the horizontal angle iron bar 22 of the frame 11 are upstanding apertured brackets 91 to which depending arms 92 are pivoted, the latter having recesses 93 at their lower ends. One of the arms 92, as clearly shown in Fig. 2, is normally urged against the pin 83 by a torsion spring 94. Further details of the box centering mechanism 13 can be found in my copending application for U. S. Letters Patent, Serial No. 40616,933, filed June 13, 1932, for Crate centering devices for lidders.

65 *The nailing mechanism 14*

The nailing mechanism 14 includes a driving head 97, front, central, and rear pairs of nail chucks 98, 99 and 100, respectively, and a driving head actuating mechanism 101.

The driving head 97 includes a pair of vertical slide shafts 102 which are slidable vertically on the side standards 21. Bolted to the upper ends of the shafts 102 are forwardly extending horizontal bars 103 having elongated slots 104 provided therein as shown in Fig. 2.

The front ends of the bars 103 are fixed to a transverse bar 105, opposite ends of the latter being braced by diagonal members 106 which are connected at their lower ends to lateral extensions 107 formed on said vertical shafts 102.

The central nail chucks 99 are rigidly secured to the aforementioned pairs of bars 29 and the front and rear chucks 98 and 100 are slidably mounted on the bars 29, as shown clearly in Figs. 2 and 5. Slidably vertically within each of the chucks 98, 99 and 100 and extending upwardly therefrom are nail drivers 110, the upper ends of the latter having threaded studs 111 which are received by the horizontal bars 103, it being noted in Fig. 21 that the studs 111 of the drivers 110 of the central chucks 99 are rigidly fixed to the bar 103 by nuts 112 and that the studs 111 of the drivers 110 of the chucks 98 and 100 are received by the aforementioned slots 104 in the bars 103. The drivers 110 of the chucks 98 and 100 are adjustable vertically relative to the

bar 103 by nuts 113 which are threaded onto the studs 111 as shown, it being noted in Fig. 21 that the nuts 113 have integral flanges 114 and sleeves 115. The sleeves 115 are of sufficient length so that when the nuts 113 are tightened against each other the space between the flanges 114 of the nuts 113 is slightly greater than the thickness of the bar 103, thus allowing the chucks 98 and 100 to slide relative to the bar 103.

10 The driving head 97 is adapted to lower and raise the drivers 110 within the chucks 98, 99 and 100 by the aforementioned actuating mechanism 101, the latter including a driven shaft 118 which is suitably journaled on the side standards 21 as shown in Fig. 1. The shaft 118 is adapted to be given a single revolution at the desire of the operator by means of a suitable power-driven clutch 119 shown diagrammatically in Figs. 1 and 2. Fixed on opposite ends of the shafts 118 are cranks 120, the latter being operatively connected to the aforementioned slide shaft extensions 107 by pitmans 121.

Provided on the front chucks 98 and the rear chucks 100, as shown in Fig. 2, are apertured ears 122 to be referred to hereinafter relative to the chuck shifting mechanism 15. Bolted to the front side of the chucks 98 and to the rear sides of the chucks 100, as shown in Figs. 8, 9 and 10, are vertical bars 123 having feet 124 formed on the lower ends thereof, it being noted that the feet 124 are positioned below the bottom of the chucks 98 and 100 as shown in Fig. 10. Fixed to the chucks 98 and 100 on opposite sides thereof from the bars 123 are bifurcated slat guides 127 which are adapted to slidably receive somewhat similar slat guides 128 provided on the central chucks 99. It will be noted in Fig. 10 that the lower surfaces of the feet 124 of the bars 123 and the guides 127 and 128 are disposed in horizontal alignment, and it will be further noted that the feet 124 and guides 127 and 128 are positioned to provide slat receiving recesses 129 below each of the nail chucks as clearly shown in Fig. 10.

45 Chuck shifting mechanism 75

The chuck shifting mechanism 15 includes an upper and a lower shaft 132 and 133 respectively, as shown in Fig. 2, these being suitably journaled at their opposite ends on the side standards 21. Fixed to the upper shaft 132, adjacent opposite ends thereof, are cranks 134 having upper and lower arms 135 and 136, respectively, and rearward extending arms 137, one of the cranks 134 being shown in Fig. 2. The free ends of the arms 135 and 136 of the cranks 134 are connected to the aforementioned ears 122 of the chucks 98 and 100 by upper and lower connecting rods 139 and 140, respectively. Fixed to opposite end portions of the lower shaft 133 are identical cranks 141, formed to provide rearward extending arms 142 and pairs of upward extending arms 143 and 144, one of the cranks 141 being shown in Fig. 2. Formed on the upper end of the arm 143 is a stop lug 145 and pivotally secured to the upper end of the arm 144 is a depending arm 146 to the lower end of which a cam 147 is fixed.

70 Rotation of the lower shaft 133 is transmitted to the upper shaft 132 by connecting rods 150, opposite ends of the latter being connected to the rearward extending arms 137 and 142 of the cranks 134 and 141, respectively, as shown in Fig. 2.

75 Pivottally hung from the aforescribed aper-

tured ears 41 of the plates 40 on the platform frame 36 are depending arms 153, one of which is shown in Fig. 2. Pivottally mounted on the lower end of the arm 153 and connected to one of the aforescribed ears 71 of the rear guide rail 16 is a horizontal arm 154. Fixed on the rear end of the arm 154 is a roller 155, the latter being disposed in the same vertical plane with the arms 143 and 144 of the crank 141.

10

Slat supporting mechanism 16

Fixed to under faces of the brackets 27 and 28 at each side of the machine 10 are identical horizontal bars 158, one of these bars being clearly shown in Figs. 5, 9 and 10. Fixed to the front end of the bars 158 are vertical curved guide plates 159, shown clearly in Figs. 1, 9 and 10. Fixed to the under side of each of the bars 158 is a plurality of vertical plates 160, as shown in Figs. 12 to 16 inclusive. Fixed to the inside edges 20 of the plates 160 is a curved plate 161, the latter being provided with large end openings 162 and a smaller central opening 163. Extending through the plates 160 is a master pin 164 on which a plurality of dogs 165 are pivottally mounted, two of these being opposite each opening 162 and one opposite the opening 163, so that these dogs can extend through said openings.

25 Each of the dogs 165 has an apertured lug 166 and an upstanding portion 167, the latter 30 having a curved face as shown in Fig. 17. Each of the dogs 165 is adapted to be urged to its normal position, as shown in Fig. 12, by contractile springs 168, the latter extending from the lugs 166 to the bar 158.

35

Slat feeding mechanism

The slat feeding mechanism 17 includes a slat carriage 172, and a carriage actuating mechanism 173, as shown in Figs. 1, 4, 5, 6 and 7. The 40 slat carriage 172 includes a pair of identical left and right-hand slides 174, these being slidably mounted on the aforementioned bars 30 and joined as shown in Fig. 1 by a horizontal bar 175. Fixed to opposite ends of the bar 175, adjacent 45 each of the slides 174, is a pair of upstanding apertured lugs 176. Each of the slides 174 has a vertical plate 177, the latter being provided with a slot 178 in the front edge thereof as shown in Fig. 4. Pivottally mounted on a suitable pin 50 179 mounted in the plate 177 adjacent its lower edge, is a forwardly extending arm 180, the latter being formed to provide a slat receiving recess 181. As shown in Figs. 4, 5, 6 and 7, the arm 180 is normally urged upwardly against a suitable 55 lug 182 provided on the lower edge of the plate 177 by a compression spring 183, the latter being urged against the under side of the arm 180 by a bolt 184 which passes loosely through a suitable opening in the arm 180 and is threadedly received by the lug 182.

Also pivottally mounted on the aforementioned pin 179 on the opposite side of the plate 177 from the arm 180 is a slat feeding arm 185, the latter extending forwardly in parallel relation 65 with the aforementioned arm 180. Projecting upwardly from a mid-portion of the arm 185 is a lug 186, to the upper end of which a roller 187 is rotatably mounted. The arm 185 is normally urged upwardly against the under side of 70 the aforementioned slide 174 by a contractile spring 188 which is suspended from one corner of the plate 177 to the upper end of the lug 186, as shown in Fig. 6. Bolted to the front end of each of the aforementioned bars 30 are cam 75

plates 192, one of the latter being shown in Fig. 4. The plates 192 are spaced from the bars 30 by spacers 193, these plates being positioned so as to contact the rollers 187 of the slides 174 in a manner to be further described hereinafter.

The slat carriage actuating mechanism 173, shown clearly in Figs. 2 and 3, includes an oscillating channel bar 195, the latter being pivotally mounted at its lower end on the angle iron bar 23 of the frame 11, as indicated at 196. The upper end of the bar 195 is connected to each of the slides 174 of the slat carriage 172 by a Y-shaped connecting rod 197. The bar 195 is adapted to be oscillated in response to vertical movement of the platform 34 by a push rod 200, as shown in Figs. 2 and 3.

The push rod 200 includes an upper tubular portion 201, the upper end of which is pivotally connected to the channel bar 195 by a pin 202. Slidably received by the tubular member 201 is a rod 203, the lower end of which is pivotally connected to a suitable lug 204, the latter being fixed to the rear edge of the platform 34, as shown in Fig. 2. The rod 203 is yieldably connected to the tube 201 by a suitable detent 206, as clearly shown in Fig. 3.

Operation

The lidding machine 10 of my invention is adapted to receive crates or boxes from a suitable delivery conveyer 220 as shown diagrammatically in Fig. 1. When the conveyer 220 feeds a crate 221 onto the platform 34 of the machine 10, the aforementioned crate stops 38 function automatically to locate the crate in proper longitudinal relation to the platform 34. This movement of the crate 221 onto the platform 34 causes the aforementioned finger 46 mounted on the bar 44 to be moved to the position shown in Fig. 40, it being noted that the bar 44 and the extension 52 pivot about their respective fulcrums against the tension of the torsion springs 49 and 54. During the interval between lidding operations the operator of the machine 10 places a stack of three slats 222 in the slat carriage 172, it being clear that this stack of slats is supported at opposite ends thereof by the arms 180 of the slides 174 of the slat carriage 172.

It also will be noted in Fig. 2 that the slat feed bar 185 of the unit 174 is now depressed in its normal position by contact of the cam plate 192 with the roller 187 of the arm 185, and that the slots 178 in the plates 171 of the slides 174 receive the spacers 193 between the cams 192 and bars 30, thus allowing the carriage 172 to be slid to its forwardmost position. The operator now depresses a foot pedal (not shown), the latter admitting fluid to the cylinder 33 of the elevator 12 which causes the platform 34 to rise. This results in the depending arms 92 of the brackets 91 engaging the pins 83 of the arms 81, and causing the latter to swing to their positions as shown in Fig. 4. Movement of the arm 81 is transmitted through the rod 84 to the arms 70 and 71, and the guide rails 75 and 76, mounted thereon, are moved inward into contact with opposite sides of the crate 221 shown in Fig. 4 so as to center this crate on the platform 34 regardless of the width of this crate.

As the rear guide rail 76 moves inwardly into contact with the crate 221, the bars 154 and 153 are moved to their positions shown in Fig. 4, it being noted that the rollers 155 on the rear ends 75 of the bars 154 engage the upstanding arms 143

of the cranks 141 causing these cranks to rotate the shaft 133 in the direction indicated by the arrow. It will be further noted in Fig. 4 that the space between the upper end of the bar 143 and the cam 147 on the depending bar 146 is equal to the diameter of the roller 155 of the bar 154, and that the cam 147 is provided to keep the crank 141 from swinging too far as a result of the impact of the roller 155 against the arm 143 of the crank 141.

As the shaft 133 is rotated in the aforescribed manner, the rods 150 on the ends of the arms 142 are pushed upwardly causing the cranks 134 on the shaft 132 to rotate in the direction of the arrow to their positions shown in Fig. 4. As the cranks 134 are actuated by the vertical rods 150, the upper and lower rods 139 and 140, respectively, cause the front and rear chucks 98 and 100 respectively to be moved inwardly towards the central chuck 99 in proper vertical alignment with the crate 221 as shown in Fig. 4. At the same time that the chucks 98 and 100 are being shifted as aforescribed, the slat feed mechanism 17 functions in the following manner:

As the platform 34 moves upward the bar 200 causes the channel bar 195 to swing rearwardly, as shown in Fig. 4. The swinging movement of the bar 195 causes the Y-shaped connecting rod 197 to draw the slat carriage 172 rearward along the bars 30. As soon as the slides 174 of the slat carriage 172 carry the stack of slats 222 to a point below the foot 124 of the bar 123 on the front chuck 98, the cam plate 192 on the bar 30 allows the slat feed bar 185 to be urged upwardly against the bottom of the stack of slats 222. Further rearward movement of the units 174 carries the slats beneath the chucks, the slat feed bar 185 continuing to urge the slats upwardly as the uppermost slats are received one at a time and retained by the aforementioned recesses 129 at the under side of each of the chucks.

As the slats 222 are being carried rearward by the carriage 177, the ends of the slats contact the curved faces of the upstanding portions 167 of the dogs 165, as shown in Fig. 13, thus causing the dogs to swing outwardly as shown in this figure. As each slat is fed into one of the opposite pairs of recesses 129 below the chucks, and the remaining slats are carried on toward the rear, the dogs 165 under that slat are allowed to move to their positions as shown in Fig. 14, thus supporting this slat in its particular pair of recesses 129.

When the crate 221 is raised to its uppermost position, as shown in Fig. 8, the slat carriage 172 has been drawn to the rear ends of the bars 30 entirely clear of the crate 221. Arrival of the crate 221 at its uppermost position causes all the dogs 165 to be moved to their inoperative positions as shown in Fig. 15, thus permitting the slats 222 to be nailed to the crate 221 by the nailing mechanism 14 in a well known manner.

During the aforescribed upward travel of the platform 34, the work centering mechanism 13 is allowed to return to its normal position shown in Fig. 11 due to disengagement of the arms 92 from the pins 83 of the depending arms 81. As the mechanism 13 returns to normal position the bar 154 on the rear guide rail 76 is pushed rearward to its normal position as shown in Fig. 8.

When the platform 34 descends to the position in which it is shown in Fig. 11, the rollers 155 of the bars 154 contact with the upstanding arms 144 of the cranks 141 and thus cause the shaft 133 to rotate in the direction indicated by the

arrow in Fig. 11, whereby the chucks 98 and 100 are shifted to normal position. As the rollers 155 ride downward along the arms 144, as shown in Fig. 11, these rollers also contact the cam 147 causing the arm 146 to be swung into contact with the stop lug 145 on the upper end of the arm 143 of the crank 141, the result being that the crank 141 is checked from swinging too far as a result of the impact of the roller 155 against the arm 144.

The operation of the aforescribed box ejector 44 during the complete cycle of operation of the machine 10 is as follows:

As the platform 34 rises, the bar 45 shown in Figs. 1, 18, 19 and 20 is drawn in the direction of the arrow in Fig. 20 by the aforescribed diagonal bar 56. When the platform 34 arrives at its uppermost position the finger 47 of the bar 45 is spring-pressed to the dotted line position shown in Fig. 20, and when the platform 34 descends, the diagonal bar 56 causes the horizontal bar 45 to roll between the rollers 43 in a direction opposite to that indicated in Fig. 20, thus bringing the finger 47 into contact with the end 25 of the crate 221 causing the latter to be ejected from the platform 34 onto a suitable crate receiving conveyer (not shown).

A more complete disclosure of the operation of the ejector 44 is made in my copending application for U. S. Letters Patent, Serial No. 526,927, filed April 1, 1931, for Box moving means.

The ejector 44 of the machine 10 differs from the disclosure of the copending application above referred to only in the size and structure of the finger 47. The finger 47 of the machine 10 is relatively long so as to engage narrow crates as well as crates of greater width, and the two-piece construction of the finger 47 enables it to swing into the dotted line position shown in Fig. 20 without requiring as much movement of the bar 45 as would be required if the finger 47 were rigid and not pivoted at its center as shown.

It is clear that the lidding machine of my invention is adapted to apply lids to crates or boxes of different widths and that the various mechanisms included in the machine, although fully automatic in operation, are simple in structure and require a minimum amount of attention.

Referring particularly to Figs. 22 to 26 inclusive, I have shown therein a portion of a modified form of lidding machine 225. The machine 225 is identical with the machine 10 with the exception of the changes and additional elements to be pointed out hereinafter. Like reference numerals are used to denote like parts in each of the machines 10 and 225.

The principal feature distinguishing the machine 225 comprises a slat storage magazine 226, the latter including a pair of vertical channel iron bars 227 which are secured in any desirable manner to the brackets 27 of the bar 25, as shown. The brackets 27, only one of which is shown in connection with the machine 225, are positioned on the bar 25 in reverse to the position of the brackets 27 of the machine 10 so as to accommodate the channel bars 227 as shown. As the channel bars 227 of the magazine 226 are identical, but one of these will be described.

Fixed to the back side of the channel bar 227 adjacent the lower end thereof, as shown in Fig. 25, is a block 228 having a pair of parallel, horizontal holes 229 bored therethrough. Slidable in the holes 229 is a pair of bars 230, the latter having fixed to opposite ends thereof a pair of collars 75 231 and a slat stack supporting member 232. The

member 232 has a horizontal finger 233 which is positioned so as to be contacted by the forward extremity of the slat receiving arm 180 as shown in Fig. 22. Fixed at its opposite ends to the block 228 and the member 232 is a contractile spring 5 234, the latter being adapted to urge the member 232 to its operative position as shown in Fig. 23.

The operation of the machine 225 is similar to that of the machine 10 excepting that instead of manually supplying the slat carriage 172 with a 10 stack of slats for each crate lidded, the operator of the machine 225 places a sufficient number of slats 222 in the magazine 226 for lidding several crates. The slats 222 gravitate to the position shown in Fig. 22, it being noted that the three 15 bottom slats are received by the recess 181 of the arm 180. When the machine 225 is actuated the slat carriage 172 is drawn rearward as aforescribed and the arms 180 carry a stack of three slats from under the stack of slats in the magazine 226 as shown in Fig. 23.

As the carriage 172 moves rearward the stack supporting member 232 is allowed to move to operative position so that the slats in the magazine 226 are supported by the finger 233 of the 25 member 232 as shown.

As the machine 225 completes its cycle of operation, the slat carriage 172 is pushed forward to the normal position shown in Fig. 22 and the arm 180 pushes the finger 233 from under the stack 30 of slats in the magazine 226, thus allowing a stack to gravitate to its position as shown.

The magazine 226 greatly facilitates the feeding of slats to the machine 225 by removing the necessity for the operator to feed a definite number of slats to the carriage 172 during each interval between lidding operations. Instead of this the only attention which the operator need give to the feeding of slats is to keep a supply of slats in the magazine 226.

Although I have shown and described but one preferred and one modified form of my invention, it is to be understood that other changes and modifications might be made in these without departing from the scope of the following claims. 45

I claim:

1. In combination: means for supporting work; means to support a plurality of slats in spaced positions preparatory to securing said slats to said work; and a carriage adapted to receive a 50 stack of slats, move said stack successively past said positions, and deposit slats from said stack in said slat supporting means at said positions.

2. In combination: means for supporting work; means to support a plurality of slats in spaced 55 positions preparatory to securing said slats to said work; and a carriage adapted to receive a stack of slats, move said stack in a substantially horizontal direction successively past said positions and deposit slats upwardly from the upper 60 end of said stack in said slat supporting means at said positions.

3. In a mechanism for positioning a slat, the combination of: means forming a downwardly disposed guide surface, there being an upward recess therein; trap means disposed opposite said recess; and means for moving a slat along said guide surface and feeding it upwardly into said recess, said trap means retaining said slat therein. 65

4. A combination as in claim 3 having a plurality of said recesses, said slat feeding means feeding a slat to each recess and said trap means retaining said slat therein, and in which said guide surface means between said recesses is tele- 75

scopic to permit variation in spacing of said recesses.

5. In a nailing machine, the combination of: a plurality of nailing chucks; means forming 5 guide surfaces at a lower level than the bottoms of said chucks, said means being broken beneath said chucks to form slat receiving recesses disposed upwardly from said surfaces; and means to temporarily support slats when the latter are 10 shifted into said recesses.

10. In a lidding machine, the combination of: means forming a downwardly disposed guide surface along which a stack of slats are adapted to be moved, there being slat receiving recesses 15 formed upwardly in said surface; and means engaging said slats when positioned in said recesses to temporarily retain said slats in said recesses.

7. In a box nailing machine, the combination of: means for supporting a box; a plurality of 20 nailing devices mounted over a given edge of said box; guides mounted on each of said devices and extending in overlapping relation into the space between adjacent devices, said guides providing 25 downwardly disposed guide surfaces for guiding slats moved slidably therebeneath in the act of positioning said slats beneath said devices; means for temporarily supporting one of said slats beneath each of said devices; and means for causing 30 relative horizontal movement between said devices to alter the spacing of slats applied by said devices to said box.

8. A combination as in claim 6 in which said first mentioned means is telescopic between said recesses to permit the spacing of said recesses to 35 be altered.

9. A combination as in claim 1 having magazine means for supplying a stack of said slats to said carriage means during each cycle of operation.

40. 10. A combination as in claim 1 in which said slat positions are spaced horizontally; means at the rear of said work support to operate said carriage in a horizontal plane between a position in front of the foremost slat position and a position 45 behind the rearmost slat position; and a slat magazine disposed adjacent the foremost position of said carriage for supplying a stack of said slats to said carriage when said carriage is adjacent said magazine.

50. 11. A combination as in claim 1 in which said slat positions are spaced horizontally; means at the rear of said work support to operate said carriage in a horizontal plane between a position in front of the foremost slat position and a position 55 behind the rearmost slat position; a slat magazine disposed adjacent the foremost position of said carriage for supplying a stack of said slats to said carriage when said carriage is adja-

cent said magazine; and means for giving relative vertical movement to said work supporting means and said slat supporting means to apply said slats to work carried on said work support, said vertical movement means actuating said carriage operating means to draw said carriage rearwardly and distribute slats in said slat positions during movement together of said work and slat supporting means, and to return said carriage forwardly to its foremost position during relative movement of said work and slat supporting means away from each other. 10

12. In a box nailing machine, the combination of: means for supporting a box; a plurality of nailing devices mounted over a given edge of 15 said box; a guide mounted on each of said devices and having a downwardly disposed slat guiding surface, said surfaces of adjacent guides having an overlapping relation; means on each of said device and guide assemblies to receive 20 and retain in position beneath the nailing device of said assembly, a slat when the latter is slid along a guiding surface of said assembly; and means for causing relative horizontal movement between said assemblies to alter the spacing 25 of slats applied by said devices to said box.

13. In a box nailing machine, the combination of: means for supporting a box; a plurality of nailing devices mounted over a given edge of 30 said box; a guide mounted on each of said devices and having a downwardly disposed slat guiding surface, said surfaces of adjacent guides having an overlapping relation; means on each of said device and guide assemblies to receive and retain in position beneath the nailing device of 35 said assembly, the topmost slat of a stack of slats when the latter is slid along a guiding surface of said assembly; and means for causing relative horizontal movement between said assemblies to alter the spacing of slats applied by 40 said devices to said box.

14. In a box nailing machine, the combination of: means for supporting a box; a plurality of nailing devices mounted over a given edge of 45 said box; a guide mounted on each of said devices and having a downwardly disposed slat guiding surface extending, parallel with said edge, towards each adjacent device, said surfaces of adjacent guides having an overlapping relation; means on each of said device and guide 50 assemblies to receive and retain in position beneath the nailing device of said assembly, a slat when the latter is slid along a guiding surface of said assembly; and means for causing relative horizontal movement between said assemblies to 55 alter the spacing of slats applied by said devices to said box.

HALE PAXTON.
